(51) LOC (10) Cl. 21-02

CLAIM

(52) U.S. Cl.

The ornamental design for a golf club head, as shown and described.

USPC D21/759

DESCRIPTION

(58) Field of Classification Search

USPC D21/736-746, 759; 473/324-331, 340,
473/341, 251-256

FIG. 1 is a top perspective view of a golf club head;
FIG. 2 is a bottom perspective view thereof;
FIG. 3 is a front view thereof;
FIG. 4 is a rear view thereof;
FIG. 5 is a top view thereof;
FIG. 6 is a bottom view thereof;
FIG. 7 is a right view thereof;
FIG. 8 is a left view thereof;
FIG. 9 is a top perspective view of a second embodiment of
the golf club head;
FIG. 10 is a bottom perspective view of FIG. 9;
FIG. 11 is a front view of FIG. 9;
FIG. 12 is a rear view of FIG. 9;
FIG. 13 is a top view of FIG. 9;
FIG. 14 is a bottom view of FIG. 9;
FIG. 15 is a right view of FIG. 9; and,
FIG. 16 is a left view of FIG. 9.

USPC D21/736-746, 759; 473/324-331, 340,
473/341, 251-256

See application file for complete search history.

The broken lines connecting the solid contour lines represent the bounds of the claim. The remaining broken lines illustrate the environment. None of the broken lines forms part of the claimed design.
